PAPER REINFORCING MACHINE

Stephen J. Baisch, Kaukauna, and Herman C. Lee, Oshkosh, Wis., assignors to Thilmany Pulp and Paper Company, Kaukauna, Wis., a corporation of Wisconsin

Application November 8, 1949, Serial No. 126,102

13 Claims. (Cl. 154—1.76)

1 The present invention relates to the art of manufacturing reinforced paper and, more particularly, it relates to the manufacture of a reinforced paper of that type which is especially resistant to tearing and breaking stresses and which includes threads or filaments disposed between two sheets of paper or the like adhered together by an adhesive.

In order to provide a paper which can be used for various heavy duty industrial purposes, as for example wrapping steel, protecting concrete constructions, covering railroad cars, etc., an extremely tough and strong paper is required. In this connection, it is well known that such a paper can be fabricated by laying threads or filaments of hemp, sisal, fiber glass or the like obliquely, in criss-cross fashion, intermediate two webs or sheets of paper. The sheets and threads are usually adhered to one another by a plastic material such as asphalt.

The known machines for providing paper of the above described construction comprise two general types. More particularly, one type of machine makes a paper having a web of intersecting threads which only extend obliquely of the sheet, while a second type employs, in addition to obliquely extending threads, strings which extend parallel to the edges of the sheet. In the second type, the oblique threads extend around strings near the side edges of the web. The present invention concerns an improved machine for making paper of the latter type.

The main object of the present invention is to provide an improved machine which is adapted to lay upon a moving sheet of paper a substantially uniform thread pattern which may extend across the full width of the sheet. A further object of the invention is to uniformly tension threads laid intermediate the sheet plies in reinforced paper of the type described above. An additional object of the invention is the provision of an improved paper reinforcing machine which is adapted to lay threads upon a sheet of adhesive coated paper at widely varying oblique angles without changing parts of the machine, which is capable of running at high speeds, and which is inexpensive to build and trouble free in operation.

Other objects and advantages of the invention will become apparent through reference to the accompanying drawings and subsequent description of the invention.

In the drawings:

Fig. 1 is a front view, partially in section, of apparatus for producing a reinforced paper in accordance with the invention.

2

Fig. 2 is a fragmentary side view of the apparatus shown in Fig. 1;

Fig. 3 is a fragmentary plan view of the apparatus shown in the previous figures;

Fig. 4 is an enlarged view taken along line 4—4 in Fig. 1; and

Fig. 5 is a view showing a modification of the invention.

Apparatus for producing reinforced paper of the type embodying threads or filaments held between a pair of sheets of paper, such as 11 and 13, usually includes, as in the present instance, means 15 for applying a tacky adhesive to one of the sheets, a pair of compression rolls 17 and 19 for pressing the sheets, 11 and 13, together, and a web laying mechanism 21 which places a web 23 of reinforcing threads on the adhesive coated sheet prior to application of the second sheet and passage of the sheets between the compression rolls, 17 and 19.

These operative parts of the apparatus may be supported upon one structure and comprise a single machine. However, in the present instance, the compression rolls 17 and 19, adhesive applicator means 15 and web laying mechanism 21 constitute separate units which are operatively interconnected.

In order to fabricate reinforced paper, shown generally at 25 in the drawings, the sheets 11 and 13 are drawn or pulled from delivery rolls (not shown) and an adhesive is placed on one of the sheets, 11 in the illustrated embodiment, by the applicator means 15. The web of threads 23 is then laid upon the coated sheet 11 and thereafter the two sheets 11 and 13 are pressed together in passing between the compression or pressure rolls, 17 and 19, which, in the illustrated construction, are vertically aligned.

As noted above, the applicator means 15 applies a plastic substance, which is preferably tacky, to the sheet 11 and it has been found that hot asphalt is very economical and practical for this purpose. The applicator means 15 includes a trough 31 containing hot asphalt and applicator rolls 33 and 35 for transferring the asphalt from the trough 31 to the surface of sheet 11. In producing some reinforced papers, it may be desirable to coat the surface of sheet 13 prior to passing into the nip between rolls 17 and 19 but means are not shown for coating this sheet in the present instance.

The pressure rolls 17 and 19 may be driven by a conventional drive mechanism (not shown) and the speed at which these rolls are rotated, 55 of course, determines the rate of the production

of the reinforced sheet 25. However, it should be noted that roll 17 is operative to pull the web 23 of threads from the thread laying mechanism 21 onto sheet 11, and consequently, the speed of the roll 17 determines the rate at which the web of threads passes onto the resulting reinforced paper product.

The web laying mechanism 21 is positioned below the compression rolls, 17 and 19, and lays a uniform thread pattern upon the adhesive coated sheet 11. This mechanism, which produces the web 23, includes a main supporting structure 39, a rotatable dome or creel member 41 which carries a supply of threads or filaments for laying in criss-cross fashion upon the sheet 11, a thread layer 45, and means 47 for applying an end or side string to the reinforced paper. In addition, the improved mechanism 21 includes a power transmission means 49 comprising a gear and chain arrangement for moving the dome member 41 and thread layer 45 in timed relation.

In the illustrated construction, a separate power means 50 is disconnectably attached to the web laying mechanism 21 and is operatively connected to the power transmission means 49. This arrangement provides flexible operation, however, the power for the gear and chain arrangement 49 may be taken from the drive mechanism for the rolls 17 and 19 by a suitable linkage in some installations. Moreover, it will be apparent to those familiar with the art that the power means 50 may be mounted on the web laying mechanism 21.

The main supporting structure 39 comprises a portable base section 51, an upstanding or vertical central supporting shaft 55 which is rigidly mounted centrally of the base section 51, a chain bar 57 supported on the upper end of the central shaft 55 which is adapted to carry the thread layer 45, and a sleeve 58 which extends around the vertical supporting shaft 55 and which is rotatably supported at its lower end upon the base section 51.

The base section 51 of the main supporting structure 39 is portable in order to permit movement of the web laying mechanism 21 for repair or other purposes and in the drawings, a track 59 (Fig. 2) is shown for carrying the mechanism. The base section 51 is fabricated from suitable structural members including a pair of channel members 61 which extend lengthwise of the track 59 and a pair of transversely extending channel members 63. These members, 61 and 63, are welded or otherwise attached at their respective ends to vertically extending bearing members 65 providing a substantially rectangular base section 51. A pair of transversely extending support members 67 extend between the longitudinally extending members 61 intermediate the ends thereof to provide support for a generally horizontally disposed plate member 69 which is welded to the support members 67. A hole 71 is formed centrally of the plate member 69 (Fig. 1). Suitable reinforcing sections 73 interconnect the support members 67 and the bearing members 65 to provide an inherently strong base structure.

The vertically extending bearing members 65 are supported on wheels 75 and are interconnected therewith by means of fork sections 77 which are connected to the individual wheels in the usual manner. The fork sections 77 include an upwardly extending shaft 81 which is proportioned to fit within the bearing member 65 75

and a lock nut 83 is threaded on the upper end of the shaft 81 to prevent loss of the wheels 75 when the mechanism 21 is lifted.

In order to facilitate movement of the web laying mechanism 21, a pair of oppositely extending V-shaped drawbars 85 are attached to the base section 51. The drawbars 85 are fabricated from suitable angle members and are attached to the base section 51 at their diverged ends by bolts 86 and the converged ends are interconnected by means of a hitch plate 87. Diagonally extending braces 89 support the outer ends of the respective drawbars 85.

To provide support for the vertically extending support shaft 55 and the rotatable sleeve 58, a supporting casting 91 is inserted in the hole 71 formed centrally of the plate member 69. The casting 91 includes a bearing cup portion 93, a shaft supporting section 95 and a lug 97 for supporting a drive shaft housing or bearing (Fig. 2). The shaft supporting portion 95 is proportioned to fit around the lower end of the central shaft 55 which is interconnected to the casting 91 by a tapered pin 99. The bearing cup portion 93 of the casting 91 is dimensioned to receive a thrust bearing 101 adapted to rotatably support the sleeve 58 at its lower end.

The central shaft 55 supports a horizontally extending plate member 103 adjacent the upper end and the shaft 55 is reduced in diameter in order to provide a rim for supporting this member. The plate 103 is rigidly positioned by a pair of pins 105 which extend through the plate member 103 and cooperating slots formed in the periphery of the shaft 55. Two studs 107 are threadedly attached to the plate member 103, each stud 107 being disposed on an opposite side of the shaft 55.

The chain bar 57, as before pointed out, provides support for the thread layer 45 and is removably attached to the supporting shaft 55. This constructional feature permits rapid replacement of the chain bar 57 in order to accommodate various widths of paper. The bar 57 is fabricated from suitably proportioned plate sections including an elongated horizontally extending top section 109 and a bottom section 111 proportioned to fit on the plate 103 locked to the upper end of the supporting shaft 55. The bottom section 111 is connected to the top section 109 by means of vertically disposed plate sections 113 and a short tubular member 115 which hold the bottom and top sections, 109 and 111, in vertically spaced relation. Vertically aligned holes are formed in the top and bottom plate sections which are proportioned to fit over the central shaft 55. The bottom plate section has a pair of holes formed therein which are positioned and dimensioned to fit over the studs 107 attached to plate member 103. A locking nut 117 is threaded on a projecting portion of the central shaft 55 to bind the chain bar 57 to the supporting structure.

The rotating sleeve 58 is fabricated from tubing or piping proportioned to fit around the vertical shaft 55 and bushings (not shown) are disposed intermediate the shaft and sleeve 58 to permit free rotation. A pair of horizontally extending annular shaped members are welded to the sleeve and provide an upper dome supporting annulus 119 and a lower dome supporting annulus 121.

As previously noted, the dome 41 is rotatably supported upon the main supporting structure 39 and provides thread which is to be placed, in

criss-cross fashion, on the coated sheet 11. The dome 41 is generally cylindrical in shape and includes a frame structure 123, an outer shell or casing 125 which is attached to the frame structure 123, thread containing means 127 and means 129 for guiding the threads from the thread containing means to a position adjacent the thread layer 45.

The dome 41 is supported by the sleeve 58 which rotates around the rigid supporting shaft 55, and consequently, the frame structure 123 of the dome is attached to the sleeve. This is done by connecting the structure 123 to the upper and lower supporting annuluses 119 and 121. The structure 123 is fabricated from suitable structural members and basically comprises upper and lower horizontally extending wheel-like structures, designated generally 131 and 133, respectively, which are disposed in vertically spaced relation. Corresponding parts of the lower structure 133 are numbered similarly to the parts of the upper structure 131 but are differentiated by the letter "a." Each of the wheel-like structures 131 and 133 includes a hub portion, 135 and 135a, proportioned to fit around the sleeve 58 and adapted for attachment to the dome supporting annuluses 119 and 121 by suitable bolts as shown at 137 and 137a. The wheel-like structures, 131 and 133, further include generally circular rims 139 and 139a which are attached to the respective hubs 135 and 135a by a plurality of radially extending spokes or braces 141 and 141a. A horizontally extending splash plate 143 is attached to the hub 135a and spokes 141a of the lower wheel-like structure 133.

The rims, 139 and 139a, of the wheel-like structures, 131 and 133, provide support for the dome casing or shell 125 which is preferably fabricated from sheet metal. The casing 125 extends upwardly and downwardly from these rims 139 and 139a, and an additional pair of rims, comprising a platform supporting rim 145 and a guard supporting rim 147, are bolted to the upper and lower edges respectively of the shell 125.

The platform supporting rim 145 is reinforced by longitudinally and transversely extending braces 149, the braces and rim providing support for a generally circular plate member 151 which forms a platform on the top of the dome 41. The circular plate 151 extends outwardly of the shell as shown at 153 and an angle member 155 extends around the outer periphery of the plate 151. A trap door 157 is provided in the platform 151 to permit ready access to the inner portion of the dome 41.

The guard supporting rim 147 is adapted to support a ring shaped guard member or bumper 159 which serves to prevent damage to the mechanism, particularly while being moved from place to place. The bumper 159 is disposed outwardly of and concentric with the casing 125, and is fabricated from tubing or the like. The guard member 159 is connected to the rim 147 by a plurality of radially extending braces 161.

The thread containing means 127, which comprises a portion of the dome 41, includes a plurality of cylindrically shaped cans 163 which are dimensioned to accommodate a spool of thread or thread cop, one of which is shown at 164 in Figs. 1 and 2, and hollow spindles 165 which are centrally disposed in the cans 163. The cans 163, which are usually fabricated from aluminum or other light weight metal, are attached to the shell 125 of the dome 41 in a conventional manner and, as will be apparent by reference to Fig. 75

2, are disposed in staggered relation so as to accommodate a maximum number of cans on the casing 125 of the dome 41. The spindles 165 are usually fabricated from maple or other hard wood and include well known means (not shown) for engaging the thread cops 164 to fixedly position them within the cans 163. Holes are formed in the cans 163 and dome casing 125 which are aligned with the hollow central portion of the spindles 165.

The means 129 provided for guiding the individual threads, indicated generally at 166, from the cans 163 to a position adjacent the thread layer, in the present instance, includes a plurality of guide tubes 168 which extend inwardly through the hollow portion of the spindles 165, upwardly within the dome 41, and through the platform member 151 to a horizontally extending tube supporting ring 167 which is disposed below the thread layer 45. The tube supporting ring 167 is supported on the platform member 151 by a plurality of spaced, upwardly extending brackets 169 and each individual guide tube 168 terminates at the tube ring 167.

A pair of horizontally extending, hoop-shaped members 171 are disposed within the dome 41 and are attached to the inner wall of the casing by generally Z-shaped brackets 173. The guide tubes 168 are attached to the hoop-shaped members 171 by brazing or soldering and provide additional support for the tubes 166. Through the described construction, lightweight tubing material may be used for the guide tubes 166 and the hoops 171 further reinforce the dome 41.

The thread layer 45 is operable to move the threads 166 generally parallel to the coated sheet 11 transversely of the line of movement, causing the threads to be laid obliquely upon the coated sheet. The thread layer 45 is supported upon the chain bar 57 and comprises an endless chain 173, a pair of end sprockets or pulleys including, in the present instance, an idler sprocket 175 and drive sprocket 177, chain guides or supports 179, outwardly extending brackets 181 (Fig. 3), and thread laying guide tubes 183 which are supported upon the chain 173 by the brackets 181.

The endless chain 173 is of conventional construction including the usual links 173a and pins 173b and is trained around the end sprockets or pulleys 175 and 177. In order to prevent sagging, intermediate the end sprockets 175 and 177, the chain guides 179, which are preferably fabricated from brass, are attached to opposite sides of the chain bar 57 to support the chain 173.

The sprockets 175 and 177 are both of well known constructions, however, the driving sprocket 177 comprises a double sprocket arrangement which drives the endless chain 173 and is driven by the power transmission means 49. Each of the sprockets 175 and 177 is supported at opposite ends of the chain bar 57 in adjustable bearings to permit proper tensioning of the chain 173. The sprockets 175 and 177 are preferably of the smallest possible diameter consistent with driving and supporting the chain 173. As a result, a maximum amount of the chain travels transversely of the sheet 11.

The brackets 181 are generally Y-shaped and include a leg section 182. The brackets are attached to the chain 173 by pins 173b, and extend horizontally outwardly from the chain to provide support for the thread laying tubes 183. The length of the leg section 182 may be varied to support the thread laying tubes 183 at the desired distance away from the chain 173.

The thread guide tubes 183 are axially vertical, in the illustrated construction, and have a highly polished inner surface to prevent catching and breaking of the threads 166 passing therethrough. The upper and lower ends of the guide tubes are flared to facilitate free passage of the threads 166. The tubes 183 may be otherwise formed as by bending them inwardly so as to decrease the angle shown in Fig. 2. As a result, a more perfect thread pattern may be placed upon the sheet 11.

As before noted, the present mechanism 21 is the type adapted to lay or place end or side strings, indicated at 184, upon an adhesive coated sheet. The means 47 for laying these strings 184 cooperatively acts with the thread layer 45 and, in the preferred construction, this string laying means is adapted to carry the threads 166 transversely outwardly from the thread laying tubes 183. The side string means 47 includes an end string supply means 185, means 187 for positioning the end strings 184 and carrying the threads 166 outwardly from the thread guide tubes 183 and guide means 189 for directing the strings 184 from the supplying means 185 to the end string positioning means 187.

In order to provide maximum resistances to tear, the end strings 184 comprises a multiplicity of threads of the type which extend diagonally of the sheet 11 and in the structure illustrated in the drawings, each end string 184 comprises 3 threads. Accordingly, 6 spools (not shown) of thread are required to supply 3 threads for each of the end strings. In view of this, the end string supplying means 185 includes six cans 191 of the type supported upon the outer casing 125 of the dome 41. These cans are attached to a generally rudder-shaped supporting member 193 in back to back relation as illustrated in Fig 2. The rudder-shaped member 193 is rigidly attached to the vertically extending shaft 55 by a clamp collar 195. The thread guide tubes 197, similar to the guide tubes 168 used for guiding the threads 166 within the dome structure 41, extend from the bottom of the respective cans 191 to an upper point on the supporting member 193 so as to be vertically aligned with openings which are formed in the chain bar 157.

The end strings 184 travel longitudinally of the chain bar 57 in opposite directions and each string spirals around an upwardly extending, generally auger-shaped tensioning element 199, guide members 201 being used to direct the threads onto these tensioning elements. After frictionally engaging the tensioning member 199, the end strings 184 pass therefrom into tubes 202 which carry the strings to a point closely adjacent the end string positioning means 187.

In the preferred construction, the end string positioning and thread carrying means 187 comprises vertically disposed wheels 203 which are located adjacent opposite ends of the chain bar 57 and extend over the end sprockets 175 and 177 and the thread guide tubes 183. Brackets 205 are bolted to the chain bar 57 to rotatably support the wheels outwardly of the ends of the bar and the outward end of each bracket 205 is bifurcated to provide a supporting yoke for the wheels 203.

Each of the wheels has a groove 207 formed in the outer periphery which is proportioned to accommodate the respective side strings 184 and, in operation, these strings travel from the out-

ward end of guide tubes 202 around a portion of the wheels 203 in the grooves 207, and up to the adhesive coated sheet 11. As a result, the wheels 203 are rotated at a peripheral speed corresponding to the velocity of the adhesive coated sheet 11.

In the illustrated construction, the wheels 203 are circular and are centrally supported. As a result, the side strings 184 are layed upon the sheet 11 a uniform distance from the edges and when the reinforced paper 25 is rolled up the strings 184 are superposed causing building up of the edges of the roll particularly when heavy weight side strings 184 are used. This difficulty may be overcome by supporting the wheels 203 off center, making the outer periphery non-circular, moving the wheels 203 horizontally in the brackets 205, or otherwise varying the distance between the side strings 184 and edge of the sheet.

In order to move the threads 166 outwardly from the thread guide tubes 183 to the side strings 184 teeth or serrations 209 are formed in the outer periphery of each wheel 203 and the wheels 203 are positioned so that these teeth 209 pick up the threads 166 from the thread guide tubes 183 as they pass thereunder. The serrated wheels 203 then carry the threads outwardly to the side strings 184. Each of the wheels 203 is preferably proportioned so as to have a radius approximating the distance between the end point of transverse travel of the thread guide tubes 183 and the side string 184. After the thread guide tubes 183 pass under the respective wheels 203, the tubes commence travel in the opposite direction and, as a result, the threads 166 are wrapped around the side strings 184.

Through the described arrangement of parts comprising the side string positioning means 47, a dome 41 of any size may be used. In addition, this means 47 permits rapid and trouble free laying of the side strings 184 upon the sheet 11.

For most efficient operation and to lay a perfect pattern upon the coated sheet 11 the thread guide tubes 183 should travel at a uniform speed transversely of and parallel to the sheet 11 and on reaching the respective end strings 184 should simultaneously stop, move around the side string 184, and assume the original velocity in the opposite direction in the same line. As this is not mechanically feasible or practical, it is desirable to approach these conditions as nearly as possible. In this connection, it will be noted that as the diameters of the end sprockets 175 and 177 are decreased, the theoretical conditions are approached.

Further, the length of the chain 173 should be equivalent to twice the distance between the side strings 184. The effect of this is to position the thread guide tubes 183, when traveling intermediate the sprockets 175 and 177, at the same position as if the tubes 183 had moved outwardly to the respective side strings 184 and immediately reversed direction. As a result of this dimensioning of the chain 173, it will be apparent that the transverse movement of the chain 173 will terminate short of the end strings 184 due to the length of chain required to pass around the sprockets 175 and 177. Accordingly, the serrated wheels 203 are provided for carrying the thread 166 in the guide tubes 183 outwardly to the end strings 184. As a result, a substantially perfect pattern is laid upon sheet 11 adjacent the side strings 184.

Other means for carrying the strings 166 outwardly from the point of termination of trans-

verse travel of the chain 173 may be provided without lengthening the chain. For example, the leg sections 182 of the guide tube supporting brackets 181 attached to chain 173 may be extended so as to carry the threads 166 outwardly of and around the side strings 184. When this is done other means may be provided for guiding the side strings 184 onto the adhesive coated sheet 11 in place of the grooved wheel 203, such as the apparatus shown in Fig. 5.

As illustrated, this apparatus comprises a curved tube 211 which may be integral with the guide tube 202 carrying the side strings 184 from the side string supply means 185. The tube 211 is supported in a bracket 213 which is bolted to the chain bar 57 as shown at 215. In operation, the thread guide tubes 183 pass around the tube 211 and the threads 166 are pulled upwardly by the adhesive coated sheet 11 onto the side strings 184.

The structure shown in Fig. 5 may also be used when a longer chain than that described above is employed. When a longer chain is operated the guide tubes 183 may be carried outwardly of the side strings independent of the dimensions of the brackets 181.

The chain bar 57 and guide tubes 183 are desirably positioned as close as possible to the point where the web 23 of threads is laid onto the adhesive coated sheet 11 so that the uniformity of the thread pattern may not be deformed by sagging of the threads 166 intermediate the thread layer 45 and sheet 11. However, the thread layer may be disposed at any distance away from the adhesive coated sheet 11 as desired and when it is so removed, it is possible to completely form the web 23 prior to application of the sheet 11.

When the pattern is completely formed prior to application the length of the chain 173 may be varied and the variation in length compensated for by adjustment of the speed of the thread layer 45. For example, if the length of the chain 173 is made four times the distance between the side strings 184 the speed of the chain may be doubled to lay a pattern substantially identical with that provided by a chain having a length twice the distance between the side strings 184. However, when the length of chain 173 exceeds or is less than twice the distance between the side strings 184 and the length is compensated for by adjustment of the rate of chain travel, it is necessary that the web 23 be substantially formed prior to application of the sheet 11. The reason for this is that the oblique angle of the threads 166 is not constant during transverse travel of the thread guide tube 183 and is only equivalent to the angle provided by the chain having a length twice the distance between the side strings 184 where the threads 166 are wrapped around the side strings 184.

The plane of the wheel 203 is preferably tangential to the roll 17 when the rolls 17 and 19 are vertically aligned, as illustrated in Fig. 2. However, the wheel 203 may be angularly disposed so as to pick up the threads 166 prior to termination of transverse travel of the thread guide tube 183. In addition, the center of the wheel 203 is desirably located in a plane which perpendicularly bisects the end sprockets 175 and 177 but this is not necessary for satisfactory operation.

The power transmission means 49 actuates various units of the thread laying mechanism 21 in timed relation and, as before pointed out, is driven by an external power means 50. Ac-

cordingly, coupling means 216 are provided for interconnecting the transmission means 49 to the external power means 50. The power transmission means 49 includes a gear, chain, and sprocket arrangement which is adapted to rotate the dome 41 and drive the thread layer 45 at correlated speeds to prevent fouling of the threads 166.

The dome 41 is rotated by a gear 217 which is keyed to the vertically extending sleeve 58 and the gear is driven by a pinion 219 which is connected to the external power means 50. Pinion 219 is fixedly attached to a vertical driven shaft 221 which is rotatably attached to a housing 223 attached to lug 97 on casting 91, the shaft 221 being driven by the coupling means 216 comprising coupling member 225 which engages a cooperating member 227 connected to the power means 50. The shaft 221 is supported in the housing 223 by thrust bearing 229 and the lower end of the shaft is journaled in bearing 231.

The thread layer 45 preferably moves around the chain bar 57 once for each revolution of the reel 41 and accordingly rotation of the reel 41 is synchronized with the movement of the thread layer 45. This is accomplished by a gear 233 which is keyed to the supporting shaft 55 so that it does not move. This gear engages a pinion gear 235 which is fixedly attached to a shaft 237, rotatably journaled on the frame structure 123 of the reel 41 in bearings 239 and 241. The pinion 235 is keyed to a spur gear 243 and the shaft 237, pinion 235, and spur gear 243 are interconnected by a lock screw 245.

Spur gear 243 engages gear 247 which is attached to an upwardly extending sleeve 249. The gear 247 and sleeve are supported upon immovable gear 233 and rotate about the shaft 55. Stationary gear 233, pinion 235, spur gear 243 and gear 247 are all disposed within an oil pan 251 which contains a suitable lubricant.

The upper end of the sleeve 249 mounts a gear 253 which is keyed to the sleeve 249. This gear 253 meshes with gear 255 which is supported in proper relation on an arm 257. This arm is clamped to the center shaft 55 and extends outwardly therefrom. The arm 257 terminates in a collar 259 which supports a rotating member 261 connected to spur gear 255 at the lower end. The rotating member 261 includes a spring and key arrangement 263 for driving a pulley 265.

The pulley 265 includes a slot (not shown) for engaging the spring and key 263 of the rotating member 259 and is supported upon a vertical shaft 267 which is attached to the chain bar 57 and guided by bushings 269 and 271. The pulley 265 is connected to a laterally spaced second pulley 273 by a V-belt 275. The second pulley 273 is fixedly attached to a vertically extending shaft 277 which is rotatably supported upon the chain bar 57. The latter shaft also supports a sprocket 279 which is spaced above the driven pulley 273. This sprocket is connected to the end sprocket 177 by means of a chain 281, the end sprocket 177 comprising the dual sprocket arrangement previously described.

By interconnecting the pulley 265 to the gear 255 with a key arrangement as described the chain bar 57 may be easily removed and replaced. This flexibility, as before pointed out, permits ready attachment of longer or shorter chain bars as desired to accommodate papers of varying widths.

The power means 50 includes a variable speed motor 283, shown schematically in the drawings,

which is connected to the coupling 216 associated with the power transmission means 49 by a key and gear arrangement. In the present instance, the motor 283 includes a horizontally extending shaft 285 which rotates a vertically extending shaft 287 by means of a pair of beveled gears, 289 and 291. The coupling member 227 is attached to the upper end of the shaft 287 and is proportioned to engage the other coupling member 225.

The shaft 287 may be driven by the driving mechanism for the compression rolls 17 and 19 to provide more economical operation. However, the separate drive arrangement described is somewhat more desirable in order to more accurately control the speed of the thread layer 45.

During operation, threads 166 will be freely supplied from spools 164 supported on the spindles 165 within the cans 163 on the dome 41. These threads pass into the guide tubes 168 and up to the thread layer tubes 183. The thread layer moves generally parallel to the adhesive coated sheet 11, transversely of the line of movement and, as a result, the thread 166 will be laid diagonally of the sheet 11. The thread layer 45 moves in opposed directions on each side of the chain bar 57 so that the threads 166 are laid upon the sheet 11 in criss-cross fashion.

The end strings 184 move upwardly from the end string supply means 185 to the chain bar 57 and travel outwardly toward the grooves 207 in the serrated wheels 203. The strings 184 are wrapped around the tensioning means 199 prior to engagement with the wheels 203 in order to maintain them in the grooves 207 and, the strings move around a portion of the wheel upwardly to the adhesive coated sheet 11.

The transversely moving thread guide tubes 183 pass around one of the end sprockets, such as 175, move to the opposite end of the chain bar 57, travel around the other end sprocket 177, and complete a continuous path. In changing directions the moving guide tubes 183 on the thread layer move below the serrated wheel 203 and as the tube 183 passes therebelow the thread 166 in that tube is caught by a tooth 209 of the wheel 203 as shown in Fig. 4.

While the traveling guide tube 183 accelerates in the opposite direction, the thread 166 is carried outwardly by the wheel 203 and engages the side string 184 at the point designated 293 in Fig. 4. As the thread 166 moves upwardly on the side string 184 and the associated guide tube 183 moves in the opposite direction, the thread 166 disengages from the tooth 209.

If the thread layer 45 travels at a rate exceeding the velocity of the adhesive coated sheet 11, the threads 166 will define a quadrilateral mesh pattern upon the sheet comprising diamonds which extend transversely of the line of movement of the sheet 11. On the other hand, if the velocity of the adhesive coated sheet 11 exceeds the velocity of the thread layer 45 the diamonds of the quadrilateral mesh pattern will extend longitudinally of the sheet. Thus, it is apparent that by varying the speed of either the sheet 11 or thread layer 45 any desired pattern may be laid in the reinforced paper 25 to provide a paper of desired characteristics. In addition, it will be noted that in order to increase the speed of operation without varying the thread pattern, both the rate of travel of the thread layer 45 and the adhesive coated sheet 11 must be increased.

In some installations, it may be desirable to

feed the web 23 directly into the nip between the pressure rolls 17 and 19. This may be done by aligning the axes of these rolls in a horizontal plane above the mechanism 21 so that the nip is located centrally of the chain bar 57. In other installations, the web 23 may be placed upon the coated sheet 11 prior to passage of the sheet onto a compression roll and a roll having a relatively small diameter may be easily used. Through the use of such a roll, threads 166 emerging from opposite sides of the chain bar 57 will be placed upon the sheet 11 at substantially the same point. These and other variations of the apparatus will be apparent to those familiar with the art and are intended to be within the scope of the invention.

In the foregoing, we have described a machine for producing reinforced paper which can be operated to provide paper having uniform strength and other characteristics, longitudinally and transversely of the sheet. Moreover, the apparatus is operable to provide reinforced papers having different characteristics with minor adjustments. In addition, the machine is easily fabricated and provides trouble-free operation. Various of the features of the invention which are believed to be new are set forth in the following claims.

We claim:

1. A mechanism for laying threads upon a continuously moving, continuous sheet which comprises means for placing a pair of laterally spaced strings upon the moving sheet parallel to the line of movement thereof, means for laying spaced threads upon said sheet diagonally of the line of movement and around said spaced strings, said last mentioned means including a pair of spaced pulleys having their centers of rotation located inwardly of said strings, an endless conveyor which travels around said pulleys, thread guides carried by said conveyor, and means for continuously moving said conveyor, and means for carrying threads outwardly from said conveyor to a point outwardly of said strings.
2. A mechanism for laying threads upon a continuously moving, continuous sheet which comprises means for placing a pair of laterally spaced strings upon the moving sheet parallel to the line of movement thereof, means for laying threads upon said sheet diagonally of the line of movement and around said spaced strings, said last mentioned means including a pair of spaced pulleys, an endless conveyor which travels around said pulleys, thread guides carried upon said conveyor, the run of said conveyor being disposed intermediate said spaced strings, means for continuously moving said conveyor, and means for carrying threads outwardly from said conveyor to a point outwardly of said strings.
3. A mechanism for placing a web of threads upon a continuously moving, continuous sheet, said mechanism including in combination means for laying a pair of laterally spaced side strings upon said moving sheet parallel to the line of movement, thread laying means for placing threads upon said sheet diagonally of the line of movement, said thread laying means including a pair of spaced sprockets the pitch circles of which are located intermediate said spaced strings, an endless conveyor which is trained around the sprockets, and thread guides supported on said conveyor and traveling intermediate said strings, said sprockets being proportioned and positioned to permit a maximum part of said conveyor to travel parallel to and transversely of said sheet,

13

means for supplying individual threads to said thread guides, means for carrying thread in said guides outwardly of the pitch line of the conveyor and around said side strings, and power means for continuously moving said thread laying means and thread supply means in timed relation with respect to said moving sheet to prevent fouling of said threads.

4. A mechanism for laying a web of threads upon a continuously moving, continuous sheet of paper which comprises a thread layer including a pair of spaced pulleys, an endless conveyor which travels around said pulleys, and thread guides attached to said conveyor, said conveyor traveling generally parallel to said moving sheet intermediate the pulleys, a rotatable structure for supplying threads to said thread guides, means for laying a string upon the sheet parallel to the line of movement thereof said string laying means being disposed outwardly of said pulleys, and intermediate the pulleys and the point of application of the string to the sheet and being operable to carry strings outwardly of the pitch circles of said pulleys, and means for supplying strings to said string laying means which is located intermediate said pulleys.

5. In a machine for laying upon a continuously moving, endless sheet a reinforcing web comprising a pair of spaced side strings and a plurality of spaced diagonal threads which extend around said side strings, alternately above and below said side strings and at an oblique angle with reference to said side strings, thereby forming on said sheet a quadrilateral mesh pattern bounded at the sides by said side strings, the combination of a roll for supporting said sheet, an endless conveyor having a pitch length substantially equal to twice the distance between said side strings, a pair of spaced pulleys around which said conveyor is trained, the axes of said pulleys being located in a common plane substantially parallel with the axis of said roll, individual thread-supplying means, said axes being disposed intermediate said side strings, thread guides carried by and spaced along said conveyor for delivering the threads to the sheet, means for continuously moving said conveyor, means disposed within the orbit of the thread guides for delivering said side strings, and guide means for laying said side strings on the sheet in the final desired position outwardly of the axes of said pulleys.

6. A mechanism for placing a web of threads upon a continuously moving, continuous sheet, said mechanism including a main supporting structure, means for laying a side string parallel to the line of movement and adjacent the outer edge of said sheet, thread laying means for placing threads upon said moving sheet diagonally of the line of movement, said thread laying means being attached to said supporting structure and including an endless chain, thread guides carried upon said chain, and a pair of spaced pulleys around which said chain is trained, said pulleys being proportioned so that a major portion of said chain travels parallel to and transversely of the line of movement of the sheet, said guides traveling inwardly of said side string, means for supplying thread to said guides, means for carrying threads in said guides outwardly from about the outermost point of travel of said guides adjacent the side string and around the string, said last mentioned means comprising a serrated wheel which is supported on said supporting structure and which extends outwardly of the outermost point of travel of

said guides, said serrated wheel engaging threads in said guides, and carrying them outwardly to said side string, and power means for actuating said chain and said thread supply means in timed relation.

7. A mechanism for placing a web of threads upon a continuously moving, continuous sheet, said web including a pair of laterally spaced side strings, said mechanism including in combination a supporting structure, thread laying means for placing threads upon said sheet diagonally of the line of movement and around said strings, said thread laying means being attached to said supporting structure and including a pair of spaced sprockets, an endless chain which is trained around said sprockets, and thread guides attached to said chain which travel in a path disposed intermediate said side strings, said sprockets being proportioned and located so that a major part of said chain travels parallel to and transversely of said moving sheet, said chain having a length closely approximating twice the distance between said laterally spaced side strings, and means attached to said supporting structure for carrying threads outwardly from said chain and around said side strings and simultaneously placing said strings on said sheet, said last mentioned means comprising a pair of spaced serrated wheels located adjacent opposite ends of transverse travel of said chain, said wheels being located above said thread guides and extending outwardly of said guides so as to pick up threads in said guides and carry them outwardly to said side strings, said wheels being formed to carry said side strings outwardly of said thread guides and lay said strings in the desired position upon said sheet.

8. A mechanism for placing a web of threads upon a continuously moving, continuous sheet, said web including a pair of laterally spaced side strings, said sheet being supported upon a roll, said mechanism including in combination, a main supporting structure, thread laying means for placing threads upon said sheet diagonally of the line of movement intermediate said side strings, said thread laying means being attached to said supporting structure and including a pair of spaced sprockets having their axes in a plane parallel to the axis of said roll, an endless chain which is trained around said sprockets, and thread guides attached to said chain, said sprockets being positioned and located so that a major part of said chain travels parallel to and transversely of said moving sheet, said chain having a length closely approximating twice the distance between said laterally spaced side strings, said thread guides traveling in a continuous path inwardly of the side strings, means for continuously moving said chain, means for carrying threads outwardly from said thread guides to said strings, said last mentioned means comprising a pair of serrated, generally vertically extending wheels which are attached to said supporting structure, each of said wheels being positioned above and extending outwardly of one of said sprockets to carry threads in said guides outwardly to said side strings, said wheels having grooves formed in the periphery thereof for guiding said side strings in the plane of said wheel up to the desired position upon said sheet.

9. A mechanism for laying threads upon a continuously moving, continuous sheet of paper which comprises a stationary supporting structure, a creel rotatably supported upon said structure, a thread laying device supported by said main structure and located between the

creel and the sheet, said thread layer including a pair of spaced pulleys, an endless conveyor trained around said pulleys, and thread guides attached to said conveyor, means for continuously moving said conveyor and means for laying side strings adjacent the outer edges of and upon said moving sheet outwardly of the centers of rotation of said pulleys, said string laying means including a guide which is supported on said structure for delivering said strings outwardly of the centers of rotation of said pulleys and in a direction parallel to said moving sheet.

10. A mechanism for laying threads upon a continuously moving, continuous sheet of paper which comprises a supporting structure including a base section and a fixed shaft, a chain bar affixed to said shaft, a creel rotatably mounted on said base section and turning about said shaft, said creel being disposed intermediate said base section and said chain bar, thread laying means movably supported upon said chain bar and including a pair of spaced sprockets, an endless chain trained around said sprockets, and thread guides attached to said chain, and means for laying a pair of spaced side strings upon said moving sheet outwardly of the centers of rotation of said sprockets.

11. A mechanism for laying threads upon a continuously moving, continuous sheet of paper supported upon a roll, said mechanism comprising a supporting structure including a base section and a fixed shaft, a creel rotatably supported on said base section and turning about said shaft, a chain bar affixed to said shaft, said creel being located intermediate said chain bar and said base section, thread laying means supported upon said chain bar and including a pair of spaced sprockets having axes disposed in a plane generally parallel to the axes of said roll, an endless chain trained around said sprockets, and thread guides attached to said chain, and means for laying a pair of spaced side strings upon said moving sheet outwardly of the centers of rotation of said sprockets, said string laying means including a pair of grooved wheels which are rotatably supported upon said chain bar and which are disposed in a plane generally parallel to the axis of said roll, said wheels being located at opposite ends of said chain bar and extending outwardly of the centers of rotation of said sprockets, and string supply means attached to said upwardly extending shaft intermediate said creel and said chain bar within the orbit of said conveyor for delivering strings outwardly to the grooves in said wheels.

12. A mechanism for placing a web of threads upon a continuous, moving sheet, the web including a pair of laterally spaced side strings, said mechanism including in combination a supporting structure, thread laying means for placing threads upon said moving sheet diagonally of the line of movement, said thread laying means being supported on said main structure and including a pair of spaced pulleys, an endless chain which is trained around said pulleys, thread guides and brackets for supporting said thread guides upon said chain, said pulleys being proportioned so that a major portion of said chain travels parallel to and transversely of the line of movement of the sheet, said pulleys being located inwardly of said side strings, said brackets being dimensioned to carry threads outwardly of said side strings, means for supplying threads to said thread guides, means for placing said side

strings upon said sheet comprising guide means attached to said supporting structure intermediate said pulleys and point of application of said strings to said sheet for guiding said strings outwardly of said pulleys and up to said sheet, and power means for actuating said chain and said supply means in timed relation to prevent fouling of said threads.

13. In a machine for laying upon a continuously moving, endless sheet a reinforcing web comprising a pair of spaced side strings and a plurality of spaced diagonal threads which extend around said side strings, alternately above and below said side strings and at an oblique angle with reference to said side strings, thereby forming on said sheet a quadrilateral mesh pattern bounded at the sides by said side strings, the combination of a roll for supporting said sheet, a supporting structure including a base section and a shaft, a chain bar attached to said shaft and extending generally perpendicularly to the axis of said shaft, a creel rotatably supported on said supporting structure intermediate said base section and said chain bar, said creel being generally cylindrical and having a plurality of thread cops supported upon its outer periphery, said creel including individual guide tubes for directing the threads from each of said thread cops to a point adjacent said chain bar, 20 a thread layer movably supported upon said chain bar, said thread layer including a pair of spaced pulleys having axes disposed in a plane generally parallel to the axis of said roll, an endless chain trained around said pulleys, a plurality of thread guides, and brackets for supporting said guides upon said chain, the pitch length of said chain closely approximating twice the distance between said side strings, said brackets being proportioned to maintain said 25 thread guides inwardly of said side strings, means for carrying said threads in said thread guides outwardly to and around said side strings and for laying said side strings upon said sheet, said last mentioned means comprising a pair of serrated wheels which are disposed in a plane generally parallel to the axis of said roll, said wheels being rotatably supported at opposite ends of said chain bar above said thread layer and extending outwardly of the path of said 30 thread guides, each of said wheels having a groove formed in the periphery thereof, a pair of string supply means attached to said supporting structure and located within the orbit of said creel and said thread layer, each of said 35 string supply means including a supply of string and guide means for directing said strings to the grooves in each of said wheels, power means for rotating said creel and driving said chain, and mechanical linkage connected between said 40 power means and said creel and said thread layer for rotating said creel one revolution for each cycle of said chain.
